METHOD OF FORMING LUMINOUS GRIDS

John J. Shively, New York, N. Y., and Miles Pennybacker, West Orange, N. J., assignors to Neosign Corporation, a corporation of Delaware

Application May 23, 1935, Serial No. 23,042

1 Claim. (CL. 49—84)

This invention relates to methods of forming luminous grids.

An object of the invention is to provide an improved method of forming grids suitable for use in luminous tube signs and the like.

A further object is to provide a method adapted to the forming of grids of the above type comprising two or more parallel legs connected by a unitary return bend or bends.

10 A still further object is to provide a method of forming grids of the above type in which all the legs lie in the same plane.

Another purpose is the provision of a method to accurately space the legs while maintaining them in the same plane.

15 A further object is the provision of a method to compensate for the distortion of the bends upon cooling, thereby insuring parallelism of the legs.

20 Other objects and advantages will appear in the following description in connection with the attached drawing, in which:

Figure 1 shows a typical grid produced in accordance with the method hereinafter described;

25 Figure 2 is a cross section of the same on the line 2—2, Figure 1;

Figure 3 shows a plan view of the apparatus in use illustrating a step in the method;

30 Figure 4 is a cross sectional view of the same on the line 4—4, Figure 3;

Figure 5 is a view similar to Figure 3 but illustrating a subsequent step in the method; and

35 Figure 6 is a fragmental view showing the means of compensating for distortion of the material when cooling.

Referring to Figure 1, a grid 10 is shown having a plurality of parallel legs 11, 12, 13, 14, 15, 40 16 and 17 connected by return bends, the grid being formed of continuous tubing terminating in housings 18 and 19 containing the usual electrodes.

45 A grid of this type formed of glass tubing is suitable for use in the changeable neon sign fully described and claimed in copending application Serial No. 22,333, filed May 20, 1935. In

such signs, the grid is clamped against the flat surface of a sheet of glass, the surface being represented by the plane B—B, Figure 2. It is obvious that for this purpose the grid 10 must be initially formed so as to be flat on the side intended to contact the surface B—B, as otherwise when clamped the grid will be subjected to bending and torsional stresses which may result in breakage.

50 In such signs it is also important that the

center distances between adjacent legs, represented in Figure 1 by a' , a^2 , a^3 , a^4 , a^5 and a^6 , be substantially equal. It has heretofore been attempted to form such grids entirely by hand, which process is slow, laborious, and requires so high a degree of skill as to make it commercially impractical. It has also been attempted to secure parallelism and even spacing of legs by forming them around a jig of such dimension that it occupied the exact space between adjacent tube walls. This method has also proved commercially impractical, due to the fact that in tubing commercially available considerable variations exist above or below the nominal diameter of the tube. When such tube is formed 10 around the type of jig described, an oversize diameter results in an oversized center distance between legs, while an undersized diameter similarly gives an undersized center distance.

These improper center distances are cumulative as the grid is formed, and when completed the grid does not fit the frame for which it is designed and is consequently unsuitable for use.

Efforts have been made to remedy the above 25 defect by pressing adjacent legs into parallel V-shaped depressions. This method has also been unsuccessful due to the fact that slight irregularities in the tube used in forming a single grid have caused the tube to sink to varying depths in the V grooves, thus destroying the flatness of the grid.

It has further been found that when adjacent legs have been disposed in parallel relation while the glass in the bend is hot, the bend in cooling distorts so as to draw the adjacent legs inward at their ends opposite the bend.

By the use of the present invention, grids may be formed from tubing of commercial deviation from nominal diameter, but in which the 40 legs are substantially parallel and evenly spaced at a predetermined center distance, and in which one side of the grid is readily maintained in a flat plane.

Referring to Figures 3 to 6 inclusive, the 45 numeral 20 indicates a platen having its flat upper surface 21 composed of a suitable heat resistant material such as asbestos composition.

Rails 22 and 23, which may be in the form 50 of angle strips, are secured to the surface 21 of platen 20, and have similarly directed surfaces 24 and 25 perpendicular thereto. Rail 23 may be pivotally secured to 21 at 26 and has at its other end a clamping screw 27 extending 55

downward through a slot 28 in platen 20 and engaging a bottom unit 29.

The rail 23 may thus be set at a small variable angle 30, Figure 6, from a position parallel with 5 rail 22 and clamped in its angular position by means of the screw 27. The ends 31 and 32 of the rails 22 and 23 remote from the clamping screw 27, are spaced so as to retain the surfaces 24 and 25 spaced substantially the desired center 10 distance a apart at this point.

The amount of distortion in cooling which occurs with tubing of a given nominal diameter, wall thickness and sharpness of bend is determined experimentally and the compensating 15 angle 30 is set accordingly.

In forming a grid 10, a length of tubing is first heated at the point to be bent and a return bend such as 33, Figure 3, is made of approximately 20 the sharpness desired. During the bending the tube is subjected to internal air pressure or "blown" in the usual manner to prevent collapse. While the bend is still plastic the legs such as 25 13 and 14, Figure 3, are placed against the rail surfaces 24 and 25 with the bend 33 adjacent the ends 31 and 32 and are pressed diagonally 30 against 24, 25 and the platen surface 21 as shown by arrows in Figure 4. The legs 13 and 14 are thus placed in the same horizontal plane, while their vertical planes correspond to the angle 30.

30 The diagonal pressure is then removed and the bend 33 allowed to cool, during which process the distortion draws the legs into parallelism. The unit is now removed from the forming device, turned horizontally through 180 degrees, and a second bend 34 made as described 35 above. The unit is again placed in the form, the leg 14 being pressed against the surface 25 and the newly directed leg 15 being pressed against surface 24 as shown in Figure 5. All 40 legs are pressed downward against the platen surface 21 at the same time, thus bringing their lower surfaces in the same plane. The bend 34 is allowed to cool, bringing tube 15 parallel to 45 14, and the above process is repeated until the required number of bends has been completed. The electrode housings 18 and 19 are then fused to the extremities of the grid and directed in any desired manner. In Figure 2 the electrode 50 18 is shown with its lower surface in the plane B-B, but it will be understood that for some purposes the electrodes may be otherwise directed, though the active tubes of the grid are maintained in the plane B-B by the method described. After the housings have been 55 attached the grid is evacuated, charged with the desired gas and sealed at any convenient point such as 35, Figure 1.

Guide lines 36 and 37 may be provided on

the surface 21 to aid the operator in maintaining the required over-all length of the grid.

From the above description, it is obvious that the invention provides a practical method of commercially forming grids of the type described. 5

Proper center distances are maintained automatically being governed by the distance a between the similarly directed surfaces 24 and 25 at points 31 and 32. Flatness of the grid is assured by the pressure noted against the surface 21, and parallelism is automatically secured by the pre-setting of the angle 30. A high commercial degree of accuracy is thus attained, and cheap and rapid production is made possible, especially as one operator may maintain several 10 grids in process at the same time, heating and making bends while others are cooling.

The invention as noted, is principally directed to the forming of grids having parallel legs, but it is obvious that it may also be used for forming 20 units having legs directed at any desired angle by placing the guides at the proper compensating angle of deviation from the desired angle.

While the invention has been described in its preferred manner it is not limited to the precise 25 structures and sequences set forth, as various modifications may be made without departing from the scope of the appended claim.

What is claimed is:

That method of forming a continuous tubular 30 grid which comprises heating a portion of a glass tube to plasticity, bending said portion through an angle of substantially 180 degrees whereby two adjacent legs are formed while applying an internal gaseous pressure to said tube 35 to prevent collapse of said portion, pressing said legs against a common plane surface and against similarly directed separate plane surfaces arranged perpendicularly to same common plane surface in spaced relation while retaining said 40 bent portion in a state of plasticity, one of said separate plane surfaces being arranged at a predetermined angle to the other, allowing said bent portion to cool whereby the distortion thereof may draw said legs through said pre- 45 determined angle into parallelism, removing said tube from said surfaces, heating and bending a second portion of said tube in the manner described and thereby forming a third leg adjacent one of said first legs, revolving said tube horizontally through substantially 180 degrees, pressing all said legs against said common plane surface and said newly formed leg and its adjacent leg against said separate surfaces in the manner described, and repeating the last named five steps 50 until the required number of legs have been formed. 55
